UNITED STATES PATENT OFFICE.

ANDREW DE VRIES, OF SOUTH BEND, INDIANA, ASSIGNOR TO WESTINGHOUSE ELECTRIC AND MANUFACTURING COMPANY, A CORPORATION OF PENNSYLVANIA.

DESIGN FOR A POST CAP.

Application filed July 14, 1927. Serial No. 22,750. Term of patent 14 years.

To all whom it may concern:

Be it known that I, ANDREW DE VRIES, a citizen of the United States, residing at South Bend, in the county of St. Joseph and State of Indiana, have invented a new, original, and ornamental Design for Post Caps, of which the following is a specification, reference being had to the accompanying drawing, constituting a part hereof.

Fig. 1 is a side elevational view of a post cap showing my new and ornamental design therefor, the dotted line portions being shown for the purpose of disclosing the manner in which the post cap is used, and

Fig. 2 is a view in perspective of my design for post caps.

I claim:

The ornamental design for a post cap as shown.

In testimony whereof, I have hereunto subscribed my name this 30th day of June, 1927.

ANDREW DE VRIES.
